John R. Kiel
ATTORNEY

UNITED STATES PATENT OFFICE.

JOHN R. KIEL, OF YOUNGSTOWN, OHIO.

DOOR HOLDER.

Application filed August 31, 1921. Serial No. 497,160.

To all whom it may concern:

Be it known that JOHN R. KIEL, citizen of the United States of America, residing at Youngstown, in the county of Mahoning 5 and State of Ohio, has invented certain new and useful Improvements in Door Holders, of which the following is a specification.

This invention relates to door holders.

The principal object is to provide a device 10 for holding doors open. A considerable amount of inconvenience has been experienced in keeping garage, barn, and doors of this nature open.

Another object is to provide a device of 15 this kind that will automatically latch when the door is swung out to the desired position.

The drawing illustrates a preferred embodiment of the invention. However, it is to be understood that in adapting the same to 20 meeting different conditions, various changes in the form, and minor details of construction may be resorted to without departing from the nature of the invention as claimed and set forth in the drawings:

25 Figure 1 is a side elevation of the device shown installed on a door jamb and door.

Figure 2 is a top plan view of the device.

Figure 3 is a detail view.

Figure 4 is a detail view.

30 By referring to Figure 1 it will be seen I have provided a bracket member 1 which is secured to a door jamb 2. This bracket member 1 has an outturned arm portion 3 and an upright portion 4. This upright portion 4 is riveted to the outer surface of the same, 35 by means of a rivet 5, a support arm 6, provided with an outturned portion 7. To the upper surface of this outturned portion 7 is secured a hinge bar 8. Over this hinge bar 40 8, I have provided a securing arm 9. This securing arm 9 is provided with a horizontal slot 10. Near the outer end of this securing arm 9, I have provided an upper vertical slot 11, and a lower vertical slot 12 which 45 join to the horizontal slot 10.

In installing this device the bracket member 1 is secured to the inner surface of the door jamb 13. The door is now swung open to a desired position for holding. Now in 50 sert the upper end 14 of the holding bracket

15 so the outturned portion 16 rests in the end of the upper vertical slot 11, and the securing arm 9 being at right angles to the door jamb 2. At this position the holding bracket should be bolted to the door 20. 55

In operating the device, simply open the door to the desired position, and the holding bracket 15 will travel outwardly in the slot 10 until it reaches the upper vertical slot 11. Now due to the slight pivot movement on the 60 rivet 5 the securing arm 9 drops downwardly and is held by the holding bracket 15 until released. When it is desired to close the door simply lift up on the thumb lift 17 and allow the holding bracket 15 to travel back 65 in the horizontal slot 10.

In order to prevent the undesired movement of the support arm 6, I have provided stops 18 and 19 formed at the upper end of the upright portion 4. 70

It will be seen by referring to Figure 3 that the holding bracket 15 is provided with a downturned portion 21 which holds the securing arm 9 in proper position.

The lower vertical slot 12 is used when 75 the device is installed on a door swinging in opposite direction from the door shown in the drawing. By this means it is not necessary to make right and left parts.

What I claim is:

1. In a device of the class described, a bracket member to be secured to a door jamb, an outturned and an upturned portion, a pivoted support arm attached to said upturned portion, stops positioned on the upper end of 85 said upturned portion, a hinge bar attached to an outturned portion of said support arm, a securing arm hinged on said hinge bar, a horizontal slot in said securing arm, an upper and lower vertical slot formed at the outer 90 end of said horizontal slot, a holding bracket attached to a door, and functioning with said securing arm and slots, substantially as described for the purpose set forth.

2. In a device of the class described, a 95 bracket member secured to a door jamb, an outturned and an upturned portion, a pivoted support arm attached to said upturned portion, stops positioned on the upper end of said upturned portion, a hinge bar attached 100

to an outturned portion of said support arm, a securing arm hinged on said hinge bar, a horizontal slot in said securing arm, an upper and lower vertical slot formed at the outer end of said horizontal slot, in combination with a holding bracket attached to a door, an outward and a downturned portion

of said holding bracket, substantially as described for the purpose set forth.

In testimony whereof I affix my signature. 10
JOHN R. KIEL.

Witnesses:

FRANK HEWITT,
MICHAEL HARTMAN.
